SPRING-NEEDLE KNITTING MACHINE.

1,235,545.

Specification of Letters Patent. Patented Aug. 7, 1917.

Application filed September 20, 1915. Serial No. 51,656.

To all whom it may concern.

Be it known that I, GEORGE P. BOSWORTH, a citizen of the United States, residing at Central Falls, Rhode Island, have invented 5 certain new and useful Improvements in Spring-Needle Knitting Machines, of which the following is a specification.

The invention relates to spring needle knitting machines of the type in which the 10 yarn is fed directly to the stems of the needles without being sunk between them by measuring sinkers and it concerns particularly the construction and arrangement of parts whereby the yarn is fed to the needles after the manner in vogue in latch 15 needle knitting, the yarn being led at a sharp angle from the thread finger downwardly to the knitting point, the web holders being controlled in a special manner to 20 permit this action to take place, and, in combination with the needles, to exert such control on the feeding strand of yarn that interlocking of this portion of the yarn under the upper nibs of the web holders will 25 be prevented during the reciprocations of the machine in making heels and toes. Further in my new organization pressing of the needle beards takes place at a point above the upper surfaces of the web holders. 30 Other features of the invention will appear hereinafter.

The invention is represented in the accompanying drawings in which:

Figure 1 is a diagram of the needles, web 35 holders and yarn feed, the needle wave being that assumed during reciprocating knitting.

Figs. 2, 3 and 4 represent different positions of the parts during the stroke of the needle cylinder leftward in the direction of 40 the arrow.

Fig. 5 represents the needles adjacent the 45 yarn feed when the direction of motion is reversed to the right.

Figs. 6 and 6^a show positions of the needles and the feed of the yarn on the stroke to the right.

Fig. 7 is a view of the knitting and guard 50 cams looking from the interior of the machine outwardly.

Fig. 8 is a bottom plan view of the web 55 holder cam ring with the beard pressers.

Figs. 9, 10 and 11 are diagrammatic views of the operation of the web holders and 60 needles at the yarn feeding point.

The spring beard needles are of substan-

tially ordinary form as shown in Figs. 9, 10 and 11 having their stems reduced or thinned at their upper ends and quite thin above their eyes which receive the points of the beards when pressed.

The web holders 12, Figs. 9-11 are of substantially ordinary form having upper and lower nibs 13, 14 with a throat between them in which the edge of the fabric is caught to hold the fabric down as the needles advance after drawing the stitch. The web holders are controlled or operated in a special manner in my present invention, which will be clear from an inspection of the cam arrangement shown in Fig. 8 taken 70 in connection with the diagrams Figs. 1 to 6^a and Figs. 9, 10 and 11.

Referring to the diagrams 1 to 6^a it will be noticed that at some points in the circle of web holders their upper nibs appear in dotted lines between the points 13^a and at other points in the needle circle the upper nibs of the said web holders appear in full lines as at 13^b. The dotted lines indicate that these web holders stand in their intermediate position *i.e.* at a point between their advanced or fabric holding position and their retracted or outermost position which they assume to allow the stitch to be drawn down into the fabric. The full lines indicate that the web holders are advanced inwardly to their full limit for engaging and holding the fabric down.

In their intermediate position the web holders lie with the forward ends of their upper nibs in the same vertical plane with the outer surfaces of the stems of the adjacent needles, as shown in Figs. 9, 10, 11 and dotted lines 13^a, Figs. 1 to 6^a. This position of the web holders is derived from the cam *a*, the heels 16 of the web holders lying in the cam groove which from point *a'* to point *a''* is concentric with the axis of the knitting head and needle circle. *a³* are the advancing cams for the web holders which project them inwardly to hold down the fabric and at *b* are shown in Fig. 8 V shaped notches or recesses to allow the web holders to recede from their intermediate positions at the points where the loops are drawn down into the fabric. Between the points *a³* and *a''* the cam groove for the web holder nibs is substantially concentric with the axis of the knitting head and between these points the web holders remain in advanced 110

or inward positions to hold the fabric down. At 17 in Fig. 8 are shown the needle beard pressers these being mounted adjustably in the cam ring, adjustment being effected by 5 the screws 18 and spring 19. The knitting points where the stitches are drawn down into the fabric are indicated at *c*.

Referring to Fig. 1 the yarn is fed directly to the needles, without the interposition of measuring sinkers by a yarn finger 20. This is located high up in relation to the knitting plane indicated by the dash line *x-x* and the yarn runs to the knitting point *c* along a straight path and at a sharp inclination as in latch needle practice. The needle beards are pressed at the point or level *d* while the beards are well above the upper nibs of the web holders.

In the stitch forming actions the yarn 20 will be fed as above stated along a straight line from the yarn feed finger to the fabric at the point where the last stitch has been drawn into the fabric and in moving along this course the yarn will pass across the front 25 edge of the upper nib of the web holder, as shown in Figs. 9 and 10 and as indicated in Fig. 1, where the yarn is shown crossing the dotted line representation of the end edge of the upper nib of the web holder. 30 The yarn is permitted to take this straight course in passing to the needles and without resting on the tops of the web holders because of the space existing within the hook of the needle due to the fact that the needle 35 stem on its front or outer edge is tapered upwardly and inwardly or away from the beard itself so that as the needle draws down space at *u* is opened up between the front edge of the upper nib of the web holder 40 and the tapered upper end of the stem within the hook, for the yarn to occupy, and this is represented by Figs. 9 and 10 in which the needle *y* has drawn down, after being pressed, part way to draw the stitch into 45 the fabric.

From what has just been said, it will be observed that the yarn is fed to the needles along a straight inclined path from the yarn finger to the fabric after the manner of 50 latch needle practice and in this feeding action of the yarn the web holders lie in their intermediate positions, as shown in said Figs. 9, 10 and 11, so as not to interfere with the direct straight course feeding of said 55 yarn.

After the stitch is drawn into the fabric the needle which has just performed this stitch drawing action is advanced again to its normal plane as shown by the needles 60 from the stitch point *c* to the point *e* in Fig. 1 and as above stated, as the needles rise the web holders are advanced inwardly to hold the fabric against the upthrust, as indicated at 13^b.

65 Because of this advance of the web holders

it is necessary to provide a way by which the 70 yarn extending from the feed finger to the fabric will be prevented from being caught under the upper nib of the web holder, when the machine reverses its stroke from the position of Fig. 4, as this locking of the yarn under the nibs would interfere with proper feeding, and the yarn is liable to be ruptured. I accomplish the desired result by 75 controlling the web holders as above stated and by utilizing the first needle of the idle set, or those which have been elevated to inoperative position in making heels and toes, to lift the feeding strand of yarn up onto the upper nib of the web holder adjacent the knitting point or in other words the point where the needle enters the fabric. This action is represented in Fig. 2, which 80 represents that the last needle *c* of the active needles has drawn its loop into the 85 fabric at *c* and that the next following needle is the first one of the idle series which has come around adjacent to the knitting point and has lifted the yarn up on the web holder at 13°. This lifting of the yarn is 90 due to the fact that the idle needle *z* as it comes to the stitch point presents the thick lower part of its stem for action against the 95 yarn and has a camming effect thereon due to inclined position of the yarn relatively to the onward moving thick stem. This action will be clear by reference to Figs. 1, 2 and Figs. 9 and 11, in which latter figures the first idle needle *z* is shown with its lower thick stem portion in line with the end of 100 the upper nib 13 of the web holder. It will be seen from Fig. 9 that the yarn on its way from the yarn finger to the fabric crosses the vertical plane along which the thick stem of needle *z* is traveling and when this stem 105 strikes the inclined yarn it lifts it up onto the upper nib as shown in Fig. 11 and holds it in this position while the stroke of the 110 needle circle in the arrow direction Figs. 1 to 4 is being completed and after the stroke 110 in the other direction takes place.

Fig. 3 represents the continuation of the stroke leftward after the action of Fig. 2 takes place, it being observed that all the active needles have completed their stitch 115 drawing action and the last few needles of this active series are partly raised to their normal plane and Fig. 4 represents the position of the needles and yarn when the stroke to the left has been completed, the 120 knitting point *c* where the yarn enters the fabric having progressed leftward from that shown in Fig. 1 to that shown in Fig. 4 and although the web holders adjacent the 125 knitting point have advanced in Figs. 3 and 4 to their full inward limit for holding the fabric down the yarn is still maintained on the one web holder above the throat of all of them so that it will not be caught in said throat. Fig. 4 also represents that all of the 130

active needles have been raised to normal plan.

It will be understood that pushing of the yarn outwardly and upwardly by the thick stem of the idle needle z begins shortly after this needle passes the yarn feed finger and it will contact with the yarn a considerable distance in advance of the point where the yarn enters the fabric.

It will also be observed that the yarn is lifted onto the web holder while it is in its intermediate position or while it is standing as shown in Figs. 9 and 11, with the point of its upper nib in the same vertical plane with the outer face or edge of the thick part of the needle stem.

Immediately after receiving the yarn on its upper nib this web holder is advanced to its full inward limit as shown by the full lines in Fig. 3 so that the yarn is held up with certainty and always by the same web holder and there is no liability for the yarn to get caught under this or any other web holders when the direction of rotation of the machine is reversed.

Fig. 5 shows the relation of the parts on the stroke in the other direction *i. e.* to the right at the time that the end of the column of idle needles is just about passing the yarn finger and with the yarn v extending vertically from the yarn finger to the fabric. The needle c' (which was the end or trailing active needle on the stroke to the left as in Figs. 1 to 4) is being picked up for narrowing and added to the column of idle needles so that when the position of Fig. 6 is reached, the yarn has been wrapped around this needle and it is lying on top of the web holder 13^a , because this web holder as above stated when in its intermediate position has its nose end in line with the outer face of the needle stem. This supports the yarn up and would not allow it to be drawn into the fabric by the needle c^2 if means were not provided whereby this web holder will free the yarn. Therefore provision is made to permit this web holder to yield or retract outwardly and allow the yarn to be drawn down into the fabric by said needle c^2 . For this purpose I make the small V-shaped notch b in the web holder cam as shown in Fig. 8 so that the web holder when it comes opposite this V-shaped space can retract, immediately after which the web holder is advanced inwardly so as to perform its regular function of holding the fabric down as the needles rise to normal plane, this inward or advance movement of the web holder being due to the cam surface at a^2 .

It will be seen from Fig. 8 that the curve a of the web holder cam is concentric from one notch b to the other and this surface a of the web holder cam holds the web hold-

ers in their intermediate position so that as above described the ends of their noses are in line with the outer face of the needle stems.

It will be seen from the above that the present spring needle machine so far as the yarn resting on one of the end web holders of the active needles is concerned is substantially the same as in latch needle practice *i. e.* to keep the yarn from becoming interlocked under the web holders.

Referring to Figs. 1 and 6 and comparing these it will be seen that in Fig. 6 the yarn is on top of the web holder adjacent the pressing point but this condition does not long prevail because a little further movement toward the right in Fig. 6 will cause the yarn, needles, and web holders to assume the relation of Fig. 1, only in reverse direction, and the yarn will be delivering substantially straight from the yarn feed to the point where the yarn enters the fabric as indicated in Fig. 6^a.

The retraction of the web holders from its intermediate position to its full inward position at the V-shaped notch b is due to the needle drawing the yarn down across the nose or upper nib of the web holder, the web holder being free to yield under the pressure of the yarn in passing down into the fabric.

In order to enable the yarn finger to be located high up in relation to the knitting plane and also permit the needles to take the yarn with certainty and to enable pressing of the needle beards to be performed while the beards are above the tops of the web holders I maintain the needles in their normal or elevated plane as shown in Fig. 1 until after they have passed the yarn feed finger. To do this I employ the divided form of upper guard cam like that described in my application No. 37022, filed June 29, 1915, consisting of the members 21^a , 21 on arms 22 pivotally mounted at 23 to the inclined sides of the pick block and pressed normally downward by springs 24 and raised alternately by the butts of the needles striking them on the reciprocations of the needle circle. These members have narrowing picks 25 combined therewith. In Fig. 7 the divided guard cam 21^a , 21 is shown in the position assumed by it on the stroke to the left, the right hand section 21 having been raised and now riding on the needle butts which after passing this section are directed downward by the inclined guard cam section 21^a to the stitch cam 26 from which it will be understood as shown in Fig. 1, that the needles do not begin to retract until after they have passed the center line of this cam set and are therefore beyond the yarn feed finger. This maintains their beards in the normal high plane and above the yarn finger and the yarn before they begin to retract and thus the yarn finger can

be located at a high point in relation to the knitting plane and the yarn can be inclined downwardly at a sharp angle and be led direct to the needle which is drawing its

5 loop into the fabric, the web holder as above stated being maintained in its intermediate position to allow the yarn to pass across its nose or nib when the wide space within the needle hook comes opposite the end of said nose.

In latch needle practice, in stocking machines, the yarn rises onto the tops of the web holders when the stroke in either direction is completed, but this action is uncer-

15 tation is completed but this action is uncertain, the yarn sometimes coming up over the web holder at the first idle needle or at the second or sometimes at the third needle. With my present invention however, the

20 web holders are so controlled or positioned that the yarn will be pushed up onto the web holder predetermined upon and no other, this being the end web holder of the active series of needles and possibility of the 25 yarn interlocking under any of the web holders will be prevented.

It will be observed that the yarn in feeding is not laid onto the upper nib or nose of the web holder but on the contrary, it passes as in latch needle practice through

passes as in latch needle practice straight to the needles from the yarn finger and it does not assume a position on top of or above the web holders until the stroke of the machine has been completed and reversal of the

35 machine is about to take place, the action in this respect being like latch needle practice but different from latch needle practice in that the yarn is lifted by the idle needle

onto the web holder and onto the same one each time, said web holder being held in a position intermediate of the full advanced and full retracted positions to allow this to be done.

What I claim is:

1. In a spring beard needle knitting machine, the combination of spring beard needles, means for feeding the yarn directly

needles, means for feeding the yarn directly to the needles without sinking it between them, web holders, means for bringing said web holders into position at the knitting point, with the ends of their upper nibs in

the plane of the outer face of the lower thick portions of the needle stems, the feeding yarn being permitted to cross the ends of said upper nibs by the presence of the relatively thin portions of the needles below

55 relatively thin portions of the needles back of their beards, said web holders being advanced by said operating means to engage and hold the fabric down as the needles rise, substantially as described.

60. 2. In a spring beard needle stocking knitting machine, the combination of spring beard needles, web holders, a yarn feed finger delivering the yarn directly to the

needles without sinking it between them,
65 said web holders at the yarn feeding point.

being located in a position intermediate of their advanced and retracted positions and with the ends of their upper nibs substantially in the plane of the outer edges of the thick lower parts of the needle stems to allow the feeding yarn to extend across said ends by the presence of the relatively thin portions of the needle back of the beards, said web holders maintaining their intermediate positions and the leading idle needle serving to lift the yarn onto the top of the upper nib of the adjacent web holder and hold it in said position while the direction of stroke is being reversed.

3. In a spring beard needle stocking knitting machine, the combination of spring beard needles, web holders, a yarn feed finger, delivering the yarn directly to the

ger delivering the yarn directly to the needles without sinking it between them, said web holders at the yarn feeding point being located in a position intermediate of their advanced and retracted positions and

and the ends of their upper nibs substantially in the plane of the outer edges of the thick lower parts of the needle stems to allow the feeding yarn to extend across said ends in the direction of the rotation of the

ends by the presence of the relatively thin portions of the needle back of the beards, said web holders maintaining their intermediate positions and the leading idle 95 needle serving to lift the yarn onto the top

in the serving to lift the jarin onto the top of the upper nib of the adjacent web holder and hold it in said position while the direction of stroke is being reversed, and means for advancing the web holders to hold down the said jarin. 10

the fabric after the feeding yarn has been lifted onto the said upper nib.

needles, web holders, means for feeding the 16
yarn directly to the needles without sinking
it between them, said web holders when at
the knitting point being in an intermediate
position with the ends of their upper nibs

substantially in the plane of the outer edge of the thick lower portion of the needle stems and allowing the yarn to feed across the ends of said nibs through the space afforded by the thin portions of the needles.

forced by the thin portions of the needles back of their beards, when the needles are retracting, the leading needle of the idle set serving to lift the yarn onto the top of said upper nibs before the reverse stroke of the

machine takes place, pick means for elevating the end needle of the active set to inoperative position and about which needle the yarn wraps as the machine is on said reverse stroke and means for effecting the

reverse stroke and means for effecting the retraction of the web holder trailing said picked needle to withdraw its upper nib from the wrapped yarn and allow the same to be drawn into the fabric by the leading one of

the remaining active needles, substantially as described.

chine the combination of spring beard needles, web holders, means for feeding the yarn directly to the needles without sinking it between them, said web holders when at 5 the knitting point being in an intermediate position with the ends of their upper nibs substantially in the plane of the outer edge of the thick lower portions of the needle stems and allowing the yarn to feed across 10 the ends of said nibs through the space afforded by the thin portions of the needles back of their beards, when the needles are retracting, the leading needle of the idle set serving to lift the yarn onto the top of said 15 upper nibs before the reverse stroke of the machine takes place, pick means for elevating the end needle of the active set to inoperative position and about which needle the yarn wraps as the machine is on said reverse 20 stroke, and means for effecting the retraction of the web holder trailing said picked needle to withdraw its upper nib from the wrapped yarn and allow the same to be drawn into the fabric by the leading one of 25 the remaining active needles, said means consisting of a notch or space in the web holder cam to allow said web holder to retract un-

der the pressure of the yarn, substantially as described.

6. In a spring beard needle knitting machine, the combination of spring beard needles, means for feeding the yarn directly to the needles without sinking it between them, web holders, means for bringing said web holders into position at the knitting point, 30 with the ends of their upper nibs in the plane of the outer face of the lower thick portions of the needle stems, the feeding yarn being permitted to cross said ends of said upper nibs by the presence of the relatively thin portions of the needles back of their beards, means for pressing the needle beards while at a point above the tops of the web holders, said web holders being advanced by said operating means to engage 35 40 45 and hold the fabric down as the needles rise, substantially as described.

In testimony whereof, I affix my signature in presence of two witnesses.

GEORGE P. BOSWORTH.
